Atty.

Patented July 28, 1925.

UNITED STATES PATENT OFFICE.

CHARLES L. MOORMAN, OF CHICAGO, ILLINOIS.

ICE-CAN CONSTRUCTION.

Application filed April 7, 1924. Serial No. 704,554.

To all whom it may concern:

Be it known that I, CHARLES L. MOORMAN, a citizen of the United States, and a resident of the city of Chicago, in the county of Cook and State of Illinois, have invented 5 certain new and useful Improvements in an Ice-Can Construction; and I do hereby declare that the following is a full, clear, and exact description of the same, reference 10 being had to the accompanying drawings, and to the numerals of reference marked thereon, which form a part of this specification.

This invention relates to ice cans as used 15 in the various brine systems for producing artificial ice, and particularly to means for introducing air under pressure into the water near the bottom of the can.

The purifying effects of aerating the 20 water as it is being frozen is well known, and such a method has been in use for some time, the apparatus comprising either an air tube suspended in the water and removed by thawing after freezing, or a tube soldered 25 to one wall of the can.

It is an object of this invention to incorporate an air tube in a seam of the ice can whereby not only is the tube fully protected 30 from injury due to the rough handling common in an ice making plant, but the manufacturing cost of assembling the tube in the can is materially reduced. Further, the ice can easily be slipped from the can as the tube presents practically no extra protuberance 35 on the interior of the can.

Other and further important objects of 40 this invention will be apparent from the disclosures in the specification and accompanying drawings.

This invention (in a preferred form) is 45 illustrated in the drawings and hereinafter more fully described.

On the drawings:

Fig. 1 is a perspective view of an ice can 45 embodying features of this invention.

Fig. 2 is an enlarged top view of the end 50 of one seam of such an ice can.

Fig. 3 is an enlarged section of such a 55 seam on the line 3-3 of Fig. 2.

Fig. 4 is a cross-section of such a seam 60 on the line 4-4 of Figure 1.

As shown on the drawings:

The sheet metal walls of an ice can are represented by the numeral 6. In the particular form shown in Fig. 1 each sheet 55 forms two sides of the can so that two diagonally opposite seams 7 result. These seams are preferably formed by folding the edges of each sheet back upon the material, interlocking the hooks so formed, soldering, 60 and providing additional securing means such as rivets or locking indentations 8 to guarantee against opening of the seam under severe service.

In the preferred form of this invention 65 one seam 7 is made as above described and the other one in a substantially the same manner with the addition of a tube 9 laid in one bend 10 of the seam, and the re-entrant end 11 of the mating bend is shortened to 70 allow space for this tube as shown in Fig. 4, where the tube is shown somewhat flattened by the operations of closing the seam. This flattening effect is desirable to reduce the bulge of the seam and to insure a smooth interior surface, although if so desired the tube may be left around throughout its length by providing a suitable depth of groove in the flattening dies used in closing 75 the seam.

As shown in Figs. 2 and 3, the return portion 80 of the bend 10 is cut away as at 12 adjacent the top of the can. The tube is left round by the provision of the extra space afforded by the cut-away portion at the top 85 to receive an air hose nipple 14. An outlet 13 is provided at the bottom to afford a discharge at 15 for the compressed air, which will thus be allowed to establish circulation 90 of the water in the can. The discharge end of the tube 9, as shown, extends nearly to the bottom 16 of the can and may consist simply of a beveled off end or a constriction of the tube.

It will thus be seen that this invention results in complete protection of the air tube 95 against damage while slipping the ice out of the can. If the tube were exposed on the walls of the can it might be torn out by the ice cake or by an adjacent can depending upon which surface it was attached to.

I am aware that numerous details of con-

struction may be varied through a wide range without departing from the principles of this invention, and I therefore do not purpose limiting the patent granted otherwise than necessitated by the prior art.

I claim as my invention:

In a vessel of the type described, a vertical interlocking return bend seam, one of the bends of which is enlarged, a tube inserted in and compressed laterally to fit said enlarged bend and having an air hose

connection at its upper end and at its lower open end projecting inwardly through an aperture in the seam.

In testimony whereof I have hereunto ¹⁵ subscribed my name in the presence of two subscribing witnesses.

CHARLES L. MOORMAN.
